LOCK-BOTTOM PUMP

Application filed December 7, 1927. Serial No. 238,265.

This invention relates generally to deep well pumps, and is more particularly concerned with pumps of the "lock-bottom" type.

As is well known, a lock-bottom pump may be characterized as a full pump assembly, including barrel and plunger, adapted to be lowered bodily into the well tubing after the latter has been set. One of the problems incident to the installation of a pump of this character is to accomplish a releasable holding connection between the working barrel and the well tubing after the pump has been lowered to position, for it is necessary, of course, that said barrel be held against longitudinal movement during subsequent stroking of the plunger. This holding connection must be a sure one, yet must be of a nature both to be entered into easily and then to be easily releasable when occasion arises for lifting the pump for inspection, replacement or repair.

Heretofore, these releasable connections have usually involved grapple fingers or expanding mandrels with their accompanying complications. While arrangements of these kinds are ordinarily satisfactory as far as positiveness of grip is concerned, they do not prove fully efficient. For instance, if the grapple fingers are of a nature to be moved positively into holding position beneath shoulders on the tubing, there must be provided means for restraining the fingers from such movement during their descension through the tubing to final position and then means must be provided to retract the fingers from holding position when it is desired to pull the barrel, this necessarily calling for complications in mechanism. The restraining mechanism is needful in order to prevent premature locking of the barrel and to prevent the fingers from contacting undesirably with the tubing or the joints thereof during descension or ascension of the barrel.

To overcome these conditions, as well as others, we devised the type of frictional lock disclosed in our copending application entitled "Pump" filed April 26, 1927, No. 186, 681. In that application, we showed a gripping member in the form of a tube slit lon-

gitudinally at a point intermediate its ends, the tube being of such material that this slitting provided a radially resilient portion. This portion was adapted to be thrust or forced with friction-tight fit into a restricted bore provided near the lower end of the tubing. The locking was thus accomplished without the use of grapple fingers with freely projecting ends and without the necessity of any auxiliary mechanism either for moving the gripping members into locking engagement with the tubing or for releasing them from such locking engagement.

While the last mentioned type of connection has been found entirely suitable under certain conditions, there are some situations where it is desirable that the gripping member engage the tubing with greater frictional force than is practicable through the use of a tube slotted in this fashion, it being obvious that if a tube so slotted be sufficiently sturdy to withstand the strains to which it is exposed during and after insertion, it is inherently limited as to the amount of weakening it may undergo in providing for a desirable degree of radial, resilient movement. Furthermore, once such a member had been fashioned for installation in a given pump, it could not be adjusted for adaptation to variations in different pumps, except that it had a slight inherent capacity to adjust itself within a small range.

Therefore, it may be considered as an object of the present invention to provide a gripping member having the advantageous points of the device shown in aforesaid copending application, as regards absence of freely projecting grapple fingers, actuating mechanism, etc., and having, in addition, much greater inherent capacity for radial expansion and contraction and thus be adapted to engage the tubing with much greater effective frictional force, though it need never engage the tubing during ascension or descension of the pump barrel therethrough. Furthermore, it is capable of adjustment within a comparatively large range to adapt it to varying situations.

Another object of our invention is to provide a gripping combination in which fingers

are provided having an appreciable inherent tendency to spring outward from the supporting means on which they are carried, and providing a keeper which may also be carried by the supporting means, this keeper being adapted to engage the free ends of the fingers to limit their outward movement. The fingers are provided with gripping portions which protrude beyond the keeper.

10 Another object of our invention is to provide a combination as just mentioned which includes adjusting means whereby the fingers may be adjusted relative to the keeper in order that the limiting of the outward movement of the free ends of the fingers may be varied.

Our invention may provide either a plurality of fingers or may provide but a single finger.

20 Another object of the invention is to provide a combination of the character described which includes a pump barrel adapted to be installed in a well tubing, a gripping member near the lower end of the barrel for holding the barrel releasably longitudinally positioned in the tubing, means near the upper end of the barrel for supporting the weight of the barrel and including a closure on the barrel adjacent to the 25 gripping means for forming a seal between the tubing and the barrel.

Another object of our invention is to provide a gripping combination for lock-bottom pumps and the like, in which gripping means designed for releasably gripping a part, and sealing means designed for forming a seal between the part and a supporting means, are both retained on a supporting means.

40 Another object of our invention is to provide a gripping combination which includes gripping members adapted to engage a part so that the gripping means and any construction secured to it releasably longitudinally positioned in the part, and a sealing means in the form of a cup leather for forming a seal between the combination and the part which it engages.

The manner in which we accomplish the above, as well as other objects and novel features of the invention, may be pointed out to better advantage in connection with the following detailed description, reference being had to the accompanying drawings, in which:

Fig. 1 shows an embodiment of our invention in connection with the tubing at the bottom of a well;

Fig. 2 is an enlarged fragmentary section, partly in elevation, on line 2—2 of Fig. 1;

Fig. 3 is an enlarged fragmentary section on line 3—3 of Fig. 1, parts being shown in elevation;

Fig. 4 is a section on line 4—4 of Fig. 3;

Fig. 5 is a detached section of the barrel-

carried gripping element, one of the spring fingers being broken off near its anchored end;

Fig. 6 is an enlarged section on line 6—6 of Fig. 3;

Fig. 7 is a view similar to Fig. 6 but showing the barrel-carried elements in the position they occupy just before or just after they have been seated within the tubing;

Fig. 8 is a view similar to Fig. 5 but showing a variational sleeve and flange mounting.

In Fig. 1 we have designated generally at 10 usual tubing adapted to be lowered into a well preparatory to pumping fluid therefrom. Secured to the lowermost end of the tubing through coupling 11, is the tubular shell 12. Broadly, it will be understood that shell 12 may be considered a part or extension of the well tubing, proper, particularly since it may be made up of standard tubing stock and needs no special preparation except cutting to proper length. Hereinafter we will refer to section 12 as a shell in order more clearly to locate various elements, but we refer to this section as a part of the tubing in the appended claims.

As a matter of convenience and economy, coupling 11 is also adapted to co-operate with a member carried by the pump, generally indicated at 13, in a manner to seal off or form a fluid-tight closure between the tubing and pump, though it will be understood this is not limitative on the invention since the sealing member may be carried by the tubing other than through coupling 11. Coupling 11 is shown in the form of a sleeve having a central internal annular flange 14^a which defines a bore 14 of a diameter sufficient to pass, with clearance, the major extent of pump 13. The upper end of flange 14^a is counterbored to provide a conical seating face 16, or face 16 may be considered as defining an inwardly and downwardly tapering counterbore 17.

The lower end of shell 12 is provided with a portion having a restricted bore which functions as a gripping member adapted to receive a gripping member carried by the pump. While this portion may be an integral part of shell 12, preferably it is in the form of a tubular shoe 18, the connection between shell and shoe preferably being through screw threads 19. Shoe 18 has an internal annular flange 20 which is of considerable longitudinal extent and defines the cylindric and relatively restricted bore 21, said bore being of lesser diameter than that of shell 12. The upper end of flange 20 is relieved at 22 to provide a flaring mouth 22^a for bore 21, the curved or inclined walls defining this flaring mouth providing means for guiding the end of the pump into the restricted bore.

Pump 13 includes working barrel 23 hav-

ing at its upper end a cap member 24, and near its lower end the standing valve 25 and gripping member 26. We have here shown member 24 as being made up in such a manner that it has several functions, though it will be understood our invention, considered broadly, is not limited to this particular structure. Member 24 is made up of the tubular, cylindric body portion 27 having at its lower end a threaded portion 28 whereby connection is made to barrel 23, an enlarged collar portion 29, and a downwardly and inwardly tapering portion 30 between portions 29 and 27, the portion 30 providing a conical, annular seating face 31 which is complementary to sealing face 16 with which it is adapted to engage when the pump is fully assembled with the tubing.

Extending upwardly from portion 29 are 20 posts 32 which support head 33, the latter having an axial bore 34 adapted to take pump rod 35, said rod being of such a diameter that there is left ample annular clearance 36 between it and portion 27 to allow 25 the free passage of fluid from barrel 23 upwardly about the rod and outwardly between posts 32 to the interior of tubing 10 at a point above the pump. The top of head 33 presents an upwardly facing shoulder 37, while the lower end of member 24 presents a downwardly facing shoulder 38, shoulders 37 and 38 thus providing longitudinally spaced and oppositely facing abutments, the purpose of which will be made apparent hereinafter. It will be seen that head 33 provides a guide member for centering the pump rod in the barrel, and also serves as an "out-board" bearing to reduce the chance of the rod being bent or sprung.

40 Connection between standing valve 25 and barrel 23 is made through a usual double-ended coupling 40, the tubular housing 41 of the standing valve comprising, in effect, a downward continuation of the barrel. Coupling 40 has the usual axial bore 42 to allow the free passage of fluid therethrough and carries a usual bridge or bumper 43 spaced from the lower end thereof to provide a stop for limiting the upward movement of the valve ball or stopper 44.

While this is in no way controlling on the invention, gripping member 26 and standing valve 25 are preferably connected through a nipple 45, said nipple and the tubular mandrel 46, which latter makes up a portion of gripping member 26, forming, in effect, an extension of barrel 23.

60 The upper end of nipple 45 is adapted to be threaded into connection with barrel 23 at 47, the end of the nipple presenting a shoulder 48 which faces and is spaced below the downwardly facing shoulder 49 presented by the internal annular flange 50 on the sleeve 41, these shoulders taking between

them the annular flange 51 on valve seat 52 to position the latter within said sleeve.

Mandrel 46 is threaded at its upper and lower ends as at 53 and 54, respectively, an external annular flange 55 being provided about the mandrel just beneath threaded portion 53. While this flange has certain functions in connection with the operation of the gripping member, this function will be described at a later point, but mention will here be made that it provides an upwardly facing annular shoulder 56, preferably somewhat arcuate as viewed in cross-section (Fig. 6) against which a cup-leather or washer 57 is adapted to be pressed by the lower end 58 of nipple 45, the latter being in threaded engagement with portion 53. Preferably, the lower end of nipple 45 is annularly relieved as at 59 to leave an annular space 60 between it and the annular flange 61 of the cup-leather, this flange engaging the inner peripheral wall of shoe-flange 20 when gripping member 26 is fully entered in gripping member 18, as shown in Fig. 6. At such a time the face 31 of member 24 is in tight engagement with face 16 of coupling 11, and it will be seen that members 24 and 57 thus close off the opposite ends of the annular space S between shell 12 and the pump barrel, preventing appreciable leakage of fluid into said space from above or below the pump barrel. The entrance of sand between the shell and barrel is thus prevented, and the danger of "sanding in" the pump is avoided, a feature of obvious advantage. However, these sealing members which provide for fluid-tight engagement between the shell and pump are of a nature to be readily released when occasion arises for pulling the pump.

Before proceeding to a detailed description of gripping member 26 and merely considering it as an element which is radially resilient and adapted to be forced with friction-tight fit into shoe 18, we will describe the more or less conventional pump plunger, the method of utilizing this for forcing the gripping member home and for releasing it from holding engagement, and will outline the normal operation of the pump. We will then go on to discuss in detail the preferred and improved type of gripping member.

While the plunger of the pump may be made up in any suitable form, we have here shown it as including a plurality of usual cups 62 provided on tubular stem 63 (Fig. 1) which is secured through coupling 64 (Fig. 2) to the lower end of usual working valve 65 having a ball stopper 66. The cups have peripheral bearing with barrel 23 while the working valve 65 is connected at 67 to the end of pump rod 35. The upper end of rod 35, where it extends above member 24, is connected through coupling 68 to sucker 130

rods 69; and it will be noted that coupling 68 presents a downwardly facing annular shoulder 70 about rod 35 which is longitudinally spaced along the rod from the upwardly facing shoulder 71 presented by working valve 65, the longitudinal spacing determining the extent of relative longitudinal movement allowed between the pump barrel and plunger 63, this extent of movement being sufficiently greater than the length of the working stroke of the plunger to permit full, uninterrupted reciprocation of the plunger during normal pump actuation.

15 The tubing 12, with its shoe 18 in place, is first set within the well. The fully assembled pump is then attached to the line of sucker rods and lowered in the usual manner, the pump during its descent being held from dropping from the rod due to the fact that shoulder 38 of member 24 rests upon shoulder 71 of valve 65. As soon as gripping member 26 comes into end engagement with shoe 18 the pump comes to rest while the sucker rods and elements carried thereby continue downwardly until shoulder 70 of coupling 68 strikes shoulder 37 of member 24. The weight of the sucker rod line is then imposed upon the pump and forces the latter downwardly to enter member 26 in restricted bore 21. If said member 26 does not immediately enter said shoe-bore, the sucker rod line may be lifted and dropped repeatedly (the lift being less than enough to unseat the gripping member from the shoe) the gripping member on the barrel thus being hammered or driven home by repeated impingement of shoulder 70 upon shoulder 37.

20 When the plunger is raised through the sucker and pump rods, fluid flows through mandrel 46, nipple 45, lifts ball 44 and passes into the bore of the barrel while the column of fluid above the closed working valve 65 is lifted and passes out the upper end of the barrel through bore 36 and between posts 32 to the tubing bore above the pump. On the subsequent down-stroke of the plunger, ball 44 is seated, and the fluid thereabove is forced through the bore of the plunger stem 63 into the barrel bore thereabove, lifting stopper 66 of valve 65 in its passage.

25 When it becomes necessary or desirable to pull the pump, the sucker rods are moved upwardly until valve 65 engages shoulder 38, whereupon continued upward pull on the sucker rods draws gripping member 26 longitudinally free from the shoe 18.

30 We will now describe the particular make-up of the preferred embodiment of gripping member 26, though it will be understood the invention, considered in its broader aspects, is not limited to all these particularities. Gripping member 26 includes the

tubular mandrel 46, heretofore described, and a sleeve 75 encircling this mandrel and having a radially resilient portion R.

35 In order to point out the characteristics of this sleeve, it will be helpful to consider the procedure in making it up, though it will be understood, of course, that the invention is in no way limited by this description of procedure. During this discussion, it will be assumed that the mandrel 46 is utilized as a supporting medium for the sleeve during certain machining operations thereon, but it will be immediately apparent that this utilization is not essential, since equivalent supporting means especially adapted for shop use may be utilized in lieu of the mandrel, and the finished sleeve may be transferred to the mandrel during the assembly of the pump.

40 Member 75 is originally in the form of a plain tube interiorly threaded at one end 76 to be taken on the threads 54 of mandrel 46. The tube is then slotted longitudinally from the other end as at 76a, leaving a plurality of upstanding fingers 77, the out-side diameter of the slotted portion, as well as of the threaded portion, being somewhat less than the diameter of the restricted bore 21 of shoe 18 and hence of less diameter than the bore of shell 12. The free ends of the fingers are then spread apart a considerable distance, for instance, to the positions shown in dotted lines in Fig. 5, the diameter of the slotted portion from a point near its lower end to the finger tips thus being made appreciably greater than the diameter of restricted bore 21. The sleeve, in this condition, is then hardened and tempered, giving resilient characteristics to the fingers, they having an inherent tendency to remain in the dotted line position of Fig. 5. The slotted portion R of the sleeve may now be considered as radially resilient.

45 The sleeve is then threaded on mandrel 46 (or upon an equivalent member, as mentioned above) it being noted that the underside of flange 55, which side faces the free end of the fingers, is undercut as at 78, the flange thus having an annular wall or extension 79 depending from the body portion thereof and overhanging the body portion of the mandrel in annularly spaced relation. While this undercutting may provide an inwardly facing shoulder 80 of any suitable form, preferably, shoulder 80 inclines downwardly and outwardly from the body portion of the mandrel, thus giving conical characteristics to undercut 78. The upper ends of fingers 77 preferably have been performed to provide tapered extremities or tips 81, the taper of the finger tips being substantially complementary to the incline of wall 80 when the fingers are in the position of Fig. 5.

50 With the fingers then radially compressed

by suitable clamps (not shown) to such a degree that the finger tips 81 are in line with undercut 78, sleeve 75 is threaded upwardly along the mandrel to enter said tips in the undercuts and the clamps are removed, it being seen that thereafter said finger tips are longitudinally overlapped by overhanging wall 78 and that flange 55 serves as a keeper or member for restraining the fingers against movement from the position to which they have been sprung towards the dotted line position. The mandrel and sleeve are threadably adjusted until, at a point somewhat above the bases of the fingers, for instance at the point *b*, the slotted portion of the sleeve is of somewhat greater diameter than the restricted bore 21 of shoe 18. The sleeve and mandrel are then mounted in a grinder or similar machine, and the fingers are ground down until the diameter of the major portion (for instance from *a* to *b*) of the radially resilient portion is just the diameter of restricted bore 21, the fingers thus being given true, arcuate outer or seating faces *F* of considerable longitudinal extent which, when the fingers are spread just enough to fit within the restricted bore of the shoe, will be complementary to the wall defining said bore. In this condition the fingers still have very appreciable inherent tendency to spring outwardly; in fact, they may have a tendency to spring apart a distance greater than the diameter of the bore of the tubing. The gripping member is then in the condition of Fig. 5, it being apparent that the inner faces *d* of the fingers incline with respect to the axis *A*, that the outer faces from *c* to *b* are parallel with face *d*, and that the outer, arcuate faces from *a*—*b* are parallel with axis *A*. The radially resilient portion when in the condition of Figs. 5 and 6 is thus of uniform diameter throughout its effective extent *a*—*b*.

The reason that the radially resilient portion is of uniform diameter throughout the length *a*—*b* and the reason that these arcuated faces are parallel to the axis *A* is that the assembly shown in Fig. 5 has been placed in a lathe and the surface from *a* to *b* has been turned so that a true cylindrical surface is obtained. It is true, therefore, that the plane of the surface *a*—*b* is parallel to the axis *A*.

When the operations just described have been completed on the assembly shown in Fig. 5 and the parts are still in the positions shown in Fig. 5, the diameter defined by the face *a*—*b* is the same diameter as the restricted bore 21. It is therefore obvious that were the assembly entered into the bore 21, it would have no gripping effect. As we have already pointed out, there is a tendency for the spring fingers to occupy positions indicated by dotted lines in Fig. 5, and the rea-

son that these fingers do not occupy the position shown by dotted lines is that the ends 81 of the fingers engage the wall 78 of the keeper flange 55. Before installing the assembly of Fig. 5 onto the barrel which must be locked in the tubing, the sleeve 75 is rotated relative to the mandrel 46 so that it is advanced away from the flange 55. This produces a relative movement between the fingers 77 and the flange 55 with the result that only the extreme end of each finger 77 will engage the lower and outer part of the wall or face 78.

It will be obvious that this adjustment which we have just explained permits the upper ends of the fingers 77 to swing outward with the result that the cylindrical face *a*—*b* is of larger diameter than the cylindrical bore 21. At this time the surface *a*—*b* is not truly cylindrical but is conical, being larger in diameter at its upper end than at its lower end because of the fact that the upper ends of the fingers 77 swing outward more than the lower ends thereof. Preferably, however, the spread allowed to the fingers by the keeper flange is not sufficient to allow them to contact with shell 12 or tubing 10 as the pump is lowered or raised therethrough, and it will be seen that during such raising or lowering the keeper flange 55 not only restrains the fingers from excess outward movement, but also overlies the free ends of the fingers so they cannot engage with the tubing or joints therein during ascension or descension of the pump. Flange 55 is, of course, of less diameter than the bore of shell 12, and preferably, though not necessarily, is of less diameter than bore 21.

The last-described condition of sleeve 75 is illustrated in Fig. 7, it being noted that flange 55 is holding the fingers from spreading outwardly into contact with shell 12 and that the diameter of the radially resilient portion of said sleeve is greater than the diameter of bore 21, though the effective extent of said portion is of less diameter at its lower end than at its upper. Now it will be seen that though the fingers have a great capacity and tendency for radial expansion and are therefore capable of exerting great force against shoe 18 when they finally are moved into engagement therewith, they have not the detrimental characteristics of widely spread fingers; and it will be further seen that due to the tapering characteristics of the finger ends and walls 80, the sleeve and mandrel may be adjusted longitudinally to vary finely the extent of radial compression needed to enter the gripping member within shoe 18. Further, it is obvious that this adjustment provides for the setting of the sleeve so it may be adapted to be entered in shoes of different effective internal diameters. While the adjustment of the fingers is

shown here as accomplished by relative movement of the mandrel body and sleeve, it is obvious that the adjustment may be considered as accomplished by relative movement of the fingers and keeper flange and any method of employing such relative movement lies within the scope of our claims. For instance, this idea may be carried out as shown in Fig. 8, wherein mandrel 46^a is in the form of a pipe having threads 53^a and 54^a at its upper and lower ends, respectively, flange 55^a being in the form of a collar threadably engaging the pipe at 53^a. Sleeve 75^a is then adapted to be secured to the pipe 75 against longitudinal movement, as by pin P, and adjustment of spring fingers 77^a is had by threading the collar 55^a along the pipe in an obvious manner. Nipple 45^a acts through cup leather 57^a to hold the collar in adjusted position.

In Fig. 7 the gripping member is shown in the condition it occupies just prior to its entry to the shoe. It will be seen that when the barrel and hence mandrel 46 is pressed downwardly, as described above, fingers 77 will engage wall 22, be thereby brought radially inward, and finally come to rest in the position of Fig. 6, it being noted that the ends 81 of the fingers are then clear of flange 55, and that due to the pre-formation of the outer faces F of the fingers, these bearing or gripping faces have full, true cylindric fit of appreciable longitudinal extent with the defining wall of bore 21, with obvious advantage. Due to the inherent tendency of the fingers to spread apart, or, expressed otherwise, the inherent tendency of the resilient portion of the sleeve to expand, the fingers have such a friction-tight fit with the shoe that accidental, longitudinal separation of the barrel and tubing is effectively resisted.

It will be seen that though it was necessary to compress the radially resilient portion only slightly to enter member 26 in the shoe, the tendency of said portion to expand is as great as though the fingers had been moved in from the dotted line positions of Fig. 5. Also, due to the inclination of faces F, entrance of the fingers to the restricted bore is accomplished with comparative ease.

When the pump is pulled, as described above, the fingers are withdrawn from the restricted bore and as soon as they clear the shoe, they are caught by flange 55 as in Fig. 7 so they will be held clear of the tubing.

As a convenient means for holding sleeve 75 from backing down from adjusted position, a collar 83 may be threaded on mandrel 46 therebelow, this collar also providing means for coupling a tubular gas anchor 84 to the mandrel. In this manner the bore of the gas anchor is put in communication with the bore of the plunger through mandrel 46, nipple 45 and sleeve 41, there being no lateral openings to the tubing bore through

these members which are intermediate the gas anchor and plunger.

It will be understood the drawings and description are to be considered merely as illustrative of and not restrictive on the broader claims appended hereto, or various changes in design, structure and arrangement may be made without departing from the spirit and scope of said claims.

I claim:

1. A gripping member or lock-bottom pumps and the like, embodying a tubular mandrel, a sleeve encircling the mandrel, said sleeve being slit longitudinally from one end thereof to provide a plurality of spring fingers forming together a radially resilient portion of the sleeve, said fingers having an appreciable inherent tendency to spring radially away from the mandrel at their free ends, and a radially extending keeper member on the mandrel adapted to engage the free ends of the fingers to limit outward radial movement of said fingers, said fingers having gripping portions which extend radially beyond the keeper.

2. A gripping member for lock-bottom pumps and the like, embodying a tubular mandrel, a sleeve encircling the mandrel, said sleeve being slit longitudinally from one end thereof to provide a plurality of spring fingers forming together a radially resilient portion of the sleeve, said fingers having an appreciable inherent tendency to spring radially away from the mandrel at their free ends, and a radially extending keeper member on the mandrel, said mandrel and sleeve being relatively movable longitudinally to engage the keeper with the free ends of the fingers to limit outward radial movement of said fingers, said fingers having gripping portions which extend radially beyond the keeper.

3. A gripping member for lock-bottom pumps and the like, embodying a tubular mandrel, a sleeve encircling the mandrel, said mandrel and sleeve being capable of relative longitudinal movement, said sleeve being slit longitudinally from one end thereof to provide a plurality of spring fingers forming together a radially resilient portion of the sleeve, said fingers having an appreciable inherent tendency to spring radially away from the mandrel at their free ends, and a radially extending keeper member on the mandrel, said keeper and the free ends of the fingers having longitudinally overlapping portions whereby the keeper is adapted to limit outward radial movement of the fingers, one of said overlapping portions inclining with respect to the mandrel axis whereby relative longitudinal movement of the mandrel and sleeve varies the extent to which the keeper permits said resilient portion to expand radially.

4. A gripping member for lock-bottom

5 pumps and the like, embodying a tubular mandrel, a sleeve encircling the mandrel, said sleeve being slit longitudinally from one end thereof to provide a plurality of 10 spring fingers forming together a radially resilient portion of the sleeve, said fingers having an appreciable inherent tendency to spring radially away from the mandrel at their free ends, and a radially extending keeper member on the mandrel adapted to engage the free ends of the fingers to limit outward radial movement of said fingers.

15 5. A gripping member for lock-bottom pumps and the like, embodying a tubular mandrel, a sleeve encircling the mandrel, said sleeve being slit longitudinally from one end thereof to provide a plurality of 20 spring fingers forming together a radially resilient portion of the sleeve, said fingers having an appreciable inherent tendency to spring radially away from the mandrel at their free ends, and a radially extending keeper member on the mandrel adapted to engage the free ends of the fingers to limit 25 outward radial movement of said fingers, said fingers having arcuate gripping faces of appreciable longitudinal extent.

30 6. A gripping member for lock-bottom pumps and the like, embodying a tubular mandrel, a sleeve encircling the mandrel, said sleeve being slit longitudinally from one end thereof to provide a plurality of 35 spring fingers forming together a radially resilient portion of the sleeve, said fingers having an appreciable inherent tendency to spring radially away from the mandrel at their free ends, and an annular flange on the mandrel and having a depending portion adapted to overhang the free ends of the 40 fingers and thereby limit outward radial movement thereof.

45 7. A gripping member for lock-bottom pumps and the like, embodying a tubular mandrel, a sleeve encircling the mandrel, said sleeve being slit longitudinally from one end thereof to provide a plurality of 50 spring fingers forming together a radially resilient portion of the sleeve, said fingers having an appreciable inherent tendency to 55 spring radially away from the mandrel at their free ends, and an annular flange on the mandrel and spaced from one end thereof, said flange having a depending portion at one side adapted to overhang the free ends 60 of the fingers and thereby limit outward radial movement thereof, and a cup washer about the mandrel at the other side of the flange and of greater diameter than the flange.

65 8. A gripping member for lock-bottom pumps and the like, embodying a tubular mandrel, a sleeve encircling the mandrel, said sleeve being slit longitudinally from one end thereof to provide a plurality of 70 spring fingers forming together a radially

resilient portion of the sleeve, said fingers having an appreciable inherent tendency to spring radially away from the mandrel at their free ends, and an annular flange on the mandrel and spaced from one end thereof, said flange having a depending portion at one side adapted to overhang the free ends of the fingers and thereby limit outward radial movement thereof, a cup washer about the mandrel at the other side of the flange and of greater diameter than the flange, and means for maintaining the washer seated on the flange.

75 9. In combination, a well tubing, a pump barrel within and annularly spaced from the tubing, a gripping member carried by the barrel near its lower end and adapted to hold the barrel releasably longitudinally positioned within the tubing bore, means near the upper end of the barrel providing a sand-tight closure between the tubing and barrel, and independent means on the barrel above but adjacent to the gripping member providing a closure between the tubing and barrel.

80 10. In combination, a well tubing whose bore has near its lower end a portion of restricted diameter, a pump barrel adapted to be lowered to position through the tubing bore, a radially resilient gripping member 85 on the barrel, said member having an inherent capacity and tendency to expand radially to a diameter appreciably greater than that of the restricted bore portion, and means on the barrel adapted to limit the extent of radial expansion of said member below that to which it is inherently capable of expanding though allowing said member to expand to a diameter greater than that of said restricted bore portion; said member being adapted to be forced into holding engagement with the tubing at the restricted portion of its bore.

90 11. The combination of a pump tubing having a seat of reduced diameter therein, 110 a pump barrel adapted to be lowered through the tubing to a predetermined position therein, fingers carried by the barrel and having an inherent tendency to spring radially outwardly therefrom, said fingers being adapted to engage said seat by virtue of said tendency when the barrel is in said predetermined position in a manner to hold the barrel releasably in that position, and means on the barrel adapted to engage said fingers during movement of the barrel to said position and limit their outward movement to a diameter less than the internal diameter of said tubing.

115 12. The combination of a pump tubing having a seat of reduced diameter therein, a pump barrel adapted to be lowered through the tubing to a predetermined position therein, fingers carried by the barrel and having an inherent tendency to spring radially out-

wardly therefrom, said fingers being adapted to engage said seat by virtue of said tendency when the barrel is in said predetermined position in a manner to hold the barrel releasably in that position, and means on the barrel adapted to engage the tips of said fingers during movement of the barrel to said position and limit their outward movement to a diameter less than the internal diameter of said tubing.

13. The combination of a pump tubing having a seat of reduced diameter therein, a pump barrel adapted to be lowered through the tubing to a predetermined position therein, expandible fingers carried by the barrel and adapted to engage said seat by virtue of expansion when the barrel is in said position and thereby hold the barrel releasably in that position, and means on the barrel adapted to engage the tips of said fingers during movement of the barrel to said position for limiting the extent of finger expansion to a diameter less than the internal diameter of said tubing.

14. A gripping combination for lock-bottom pumps and the like comprising: a supporting means; a spring finger supported by said supporting means, one end of said spring finger being attached to said supporting means and the other end being free to move inward and outward, said finger having an appreciable inherent tendency to spring outward from said supporting means at its free end; and a keeper carried by said supporting means adapted to engage the free end of the finger to limit outward movement of said finger, said finger having a gripping portion which extends outward beyond said keeper.

15. A gripping combination for lock-bottom pumps and the like comprising: a supporting means; a spring finger supported by said supporting means, one end of said spring finger being attached to said supporting means and the other end being free to move inward and outward, said finger having an appreciable inherent tendency to spring outward from said supporting means at its free end; a keeper carried by said supporting means adapted to engage the free end of the finger to limit outward movement of said finger, said finger having a gripping portion which extends outward beyond said keeper; and adjusting means whereby said finger may be adjusted relative to said keeper in order that the limiting of the outward movement of the free end of the finger may be varied.

16. A gripping combination for lock-bottom pumps and the like comprising: a supporting means; a plurality of spring fingers supported by said supporting means, said fingers having free ends and having an inherent tendency to spring outward from said supporting means at the free ends; a keeper

carried by said supporting means adapted to engage said free ends to limit the outward movement, said fingers having gripping portions which extend outward beyond said keeper; and adjusting means whereby said fingers may be adjusted relative to said keeper in order that the limiting of the outward movement of the free ends of said fingers may be varied.

17. In combination: a well tubing; a pump barrel within and annularly spaced from said tubing; a gripping member carried by said barrel near its lower end and adapted to hold said barrel releasably longitudinally positioned in said tubing; means near the upper end of said barrel for supporting the weight of said barrel; and an independent closure on said barrel adjacent said gripping means forming a seal between said tubing and said barrel.

18. In combination: a well tubing; a pump barrel within and annularly spaced from said tubing; a gripping member carried by said barrel near its lower end and adapted to hold said barrel releasably longitudinally positioned in said tubing, said gripping member having a longitudinal slit; means near the upper end of said barrel for supporting the weight of said barrel; and an independent closure on said barrel adjacent said gripping means forming a seal between said tubing and said barrel.

19. A gripping combination for lock-bottom pumps and the like comprising: a central supporting means; a gripping means carried by said supporting means, said gripping means being designed for releasably gripping a part; and an independent sealing means on said supporting means for forming a seal between said supporting means and said part.

20. A gripping combination for lock-bottom pumps and the like comprising: a supporting means; a spring finger supported by said supporting means, one end of said spring finger being attached to said supporting means and the other end being free to move inward and outward, said finger having an appreciable inherent tendency to spring outward from said supporting means at its free end; a keeper carried by said supporting means adapted to engage the free end of the finger to limit outward movement of said finger, said finger having a gripping portion which extends outward beyond said keeper; and sealing means carried by said supporting means.

21. A gripping combination for lock-bottom pumps and the like comprising: a supporting means; a spring finger supported by said supporting means, one end of said spring finger being attached to said supporting means and the other end being free to move inward and outward, said finger having an appreciable inherent tendency to

spring outward from said supporting means at its free end; a keeper carried by said supporting means adapted to engage the free end of the finger to limit outward movement of said finger, said finger having a gripping portion which extends outward beyond said keeper; adjusting means whereby said finger may be adjusted relative to said keeper in order that the limiting of the outward movement of the free end of the finger may be varied; and sealing means carried by said supporting means.

22. A gripping combination for lock-bottom pumps and the like comprising: a supporting means; a plurality of spring fingers supported by said supporting means, said fingers having free ends and having an inherent tendency to spring outward from said supporting means at the free ends; a keeper carried by said supporting means adapted to engage said free ends to limit the outward movement, said fingers having gripping portions which extend outward beyond said keeper; and sealing means carried by said supporting means.

23. A gripping combination for lock-bottom pumps and the like comprising: a supporting means; a plurality of spring fingers supported by said supporting means, said fingers having free ends and having an inherent tendency to spring outward from said supporting means at the free ends; a keeper carried by said supporting means adapted to engage said free ends to limit the outward movement, said fingers having gripping portions which extend outward beyond said keeper; adjusting means whereby said fingers may be adjusted relative to said keeper in order that the limiting of the outward movement of the free ends of said fingers may be varied; and sealing means carried by said supporting means.

In witness that we claim the foregoing we have hereunto subscribed our names this 16th
45 day of November, 1927.

WILLISIE A. S. THOMPSON.
